(57) **CLAIM**

We claim the ornamental design for a travel pillow, as shown and described.

DESCRIPTION

FIG. 1 is a right perspective view of the travel pillow shown in use as it would be worn by a person;

FIG. 2 is a right perspective view of the travel pillow;

FIG. 3 is a right side view thereof, with the left side view being a mirror image;

FIG. 4 is a top plan view thereof;

FIG. 5 is a bottom plan view thereof;

FIG. 6 is a rear view thereof; and,

FIG. 7 is a front view thereof.

The broken lines showing the person in FIG. 1 are for illustrative purposes only and form no part of the claimed design.
